GRAIN DRIER

Ben L. Tomlinson, Minneapolis, Minn., assignor
to Arid-Aire Manufacturing Company, Minneapolis, Minn., a corporation of Minnesota

Application September 17, 1952, Serial No. 310,014

12 Claims. (Cl. 263—8)

1

This invention relates to grain dryers. More particularly, it relates to grain dryers of the type using an endless conveyor continuously passing grain through a drying chamber, the grain being completely dried while passing through the chamber and thereafter discharged for storing.

This invention constitutes improvements over the grain dryers shown in patent application, S. N. 244,972 entitled Grain Dryer filed by Donald E. Carlson and myself as joint inventors on September 4, 1951, and also to the grain dryer disclosed and claimed in Patent No. 2,490,176 issued December 6, 1949, to William E. Tomlinson and me. Although the grain dryers shown in this patent and this application function in a highly satisfactory manner, I have found that there is a strong demand among the larger grain elevator operators for a grain dryer having increased capacity. One such dryer, as is disclosed in this prior patent and application, will handle the normal operating load of most elevator installations, but for the larger ones such dryers do not have sufficient capacity individually and hence two or more of the same are required. Since these dryers represent a substantial outlay for construction and materials, any means by which the capacity of such a dryer can be increased is of vast importance to the grain industry. My invention provides a solution for this problem and need.

It is a general object of my invention to provide a novel and improved grain dryer of increased capacity.

A more specific object is to provide a novel and improved grain dryer of the type utilizing an endless conveyor upon which the grain is dried, this dryer functioning in an improved manner and substantially increasing the amount of grain which may be dried therein.

Another object is to provide a novel and improved grain dryer wherein the grain is carried throughout the length of the unit through a heating chamber and then reversed in direction and carried again throughout the length of the unit while being cooled whereby the capacity of the unit is increased and improved drying is attained.

Another object is to provide a grain drying unit which will have a greater capacity without increasing the overall size of the drying unit.

These and other objects and advantages of my invention will more fully appear from the following description made in connection with the accompanying drawings, wherein like reference characters refer to the same or similar parts throughout the several views, and in which:

Fig. 1 is a diagrammatic perspective view of one

embodiment of my invention with portions thereof broken away to show the interior construction; Fig. 2 is a vertical sectional view taken approximately along line 2—2 of Fig. 4; 5 Fig. 3 is a vertical sectional view taken approximately along line 3—3 of Fig. 4; Fig. 4 is a side elevational view of one embodiment of my device taken from the side along which the cooling conveyor passes; 10 Fig. 5 is a fragmentary plan view of a side portion of one of the conveyors; Fig. 6 is a vertical sectional view taken along line 6—6 of Fig. 5; Fig. 7 is a fragmentary vertical and longitudinal sectional view taken approximately along line 7—7 of Fig. 5; and 15 Fig. 8 is a transverse vertical sectional view taken through the agitator. One embodiment of my invention, as shown in Figs. 1—8, may include an elongated housing indicated generally as 10 and having insulated side walls 11 and 12, a front end 13, a rear end 14 and a top 15, a portion 16 of which is open to permit air to pass readily therethrough. The entire housing is mounted upon a pair of spaced longitudinally extending skids 17 and 18. As best shown in Fig. 1, the housing 10 has a grain intake 19 and a grain discharge outlet 20.

Extending longitudinally of the housing 10 throughout its interior is a partition 21 which divides the interior of the housing 10 into a hot chamber 22 and a cooling chamber 23. The hot chamber 22 has an air intake 24 and the opening 16 serves as an air discharge outlet therefor. 35 The cooling chamber 23 has an air intake 25 and the lower portion thereof is open as at 26 to provide an air discharge outlet for the same.

Immediately beneath the grain intake 19 is a hopper 27 which has a divider plate 28 therewithin to distribute the grain across the entire width of the hopper as it enters the same. One side of the hopper is provided with a vertically movable gate 29 and this gate has a control mechanism 30 for moving the gate vertically to regulate the flow of grain downwardly therethrough.

As the grain passes through the gate 29 it is deposited upon the drying conveyor indicated generally as 31, this drying conveyor being of the endless and porous type. It has a receiving end 32 and a discharge end 33 and extends throughout the length of the housing 10. As can be readily seen in Fig. 1, this conveyor 31 is mounted for revolution about a pair of longitudinally spaced horizontal axes one of which is at each end of the housing. At the receiving end 32 of

55

the conveyor the conveyor passes around a shaft 34 which has a sprocket 35 at each of its ends, these sprockets having relatively wide teeth 36 and being separated by a relatively narrow recess as can best be seen by referring to Fig. 7 which discloses the shaft 37 at the discharge end 33 of the conveyor bearing a sprocket 38 formed similarly to the sprocket 35.

The conveyor 31 is formed of a plurality of parallel transversely extending panels 39 which have a plurality of apertures formed therethrough throughout their length. These apertures 40 are evenly spaced and are of approximately .0625 inch in diameter. The side edges of these panels 39, as best shown in Fig. 6, are reversed upon themselves, the leading edge 41 being reversed upon itself and then bent downwardly as at 42 to provide a downwardly extending flange 43. The trailing edge is bent downwardly as at 44 to form a depending flange 45 and then reversed upon itself to extend upwardly and then forwardly again as best shown in Fig. 6. These edges are reversed upon themselves to provide strength. It should be noted that the leading edge 41 of each panel extends slightly above the trailing edge of the preceding panel but in close proximity thereto so as to prevent any appreciable passage of grain therebetween. As these panels 39 pass around the horizontal axes at each end of the conveyor, the space between the trailing edge of the preceding panel and the forwardmost portion of its following panel widens and permits any grain which may have worked therebetween to freely drop from the conveyor. Thus the conveyor has a unique self-cleaning feature due to its construction.

Mounted on each end of each of the panels 39 is a side guard 46 which is comprised of a horizontal plate member 47 and an upstanding flange member 48. Each of these flange members 48 is formed slightly diagonally with respect to the horizontal portion 47 so that the forward end 49 thereof extends inwardly slightly farther than the rearward end 50 thereof. This causes the forward end 49 to extend inside of the rearward end 50 of the preceding flange as can best be seen in Fig. 6. In this manner, the side guards overlap and prevent the escape of any grain over the sides of the conveyor. The inner link strap 51 has an inwardly extending horizontal flange 52 which extends inwardly beneath the horizontal portion 47 of each side guard and is connected thereto and to the end of the panel 49 by bolts 53. Each of these link straps 51 has a roller pin 54 extending outwardly therefrom and carrying a spacing roller 55 thereupon. Mounted on this roller pin 54 outside of the roller 55 is an outer link strap 56 which is held in place by a cotter pin 57. As can best be seen in Fig. 5, the positioning of these outer link straps 56 is altered so that alternate link straps are positioned inwardly of the others. The length of these inner and outer link straps 51 and 56 is equal to the spacing between the recesses or grooves in the sprockets so that the rollers 55 will fit thereinto and serve to drive the conveyor when the sprockets turn.

The drying conveyor 31 empties at the rear end of the unit into a trough 58. This trough 58 has a transversely extending auger 59 mounted in the bottom portions thereof. As can best be seen in Fig. 1, the auger 59 has opposite flights at the opposite end portions thereof which carry the grain to a chute 60 which has a divider plate 61 mounted centrally thereof to cause the grain

to spread out evenly upon the upper surface of the receiving end of the cooling conveyor indicated generally as 62. A leveling gate 63, as best shown in Fig. 7, is pivoted at 64 to permit the same to ride upwardly and downwardly over the grain and to level the grain into an even stratum upon the upper surface of the cooling conveyor 62.

The cooling conveyor 62 is constructed similarly to the drying conveyor 31 with the exception that it is substantially narrower. It is operated at approximately three times the speed of the drying conveyor 31 and hence can easily carry the entire load of grain which is discharged from the drying conveyor 31. The panels and linkage of the cooling conveyor 62 is constructed identically with the panels and linkage of the drying conveyor so that no further description of these parts is deemed necessary. The cooling conveyor 62 has a receiving end 65 and a discharge end 66 the latter of which discharges the grain outwardly through a discharge outlet 67 upon a conveyor or other equipment (not shown) for conveying the dried grain to a storage location.

The driving power for the conveyors is provided by a motor 68 which has a variable speed mechanism known as a Reeves drive 69, a gear reducer 70 and a chain 71 which extends downwardly to drive the drive shaft 72 which is the shaft which carries the discharge end of the cooling conveyor 62 and causes the latter to revolve thereabout. The countershaft 73 is provided with a chain 74 which passes around a pair of idlers 75 and drives the drying conveyor 31 by passing around a sprocket 76 mounted on one end of the shaft 37. Thus it can be readily seen that the motor 68 not only drives the cooling conveyor 62, but it also drives the drying conveyor 31.

Extending longitudinally of the unit and mounted at the bottom of the generally V-shaped lower walls of the heating chamber, is a clean-out auger 76. This clean-out auger is driven by a bevel gear 77 which is carried on the outer end of a countershaft 78 which in turn is connected by a universal joint to the other end of the countershaft 73. This clean-out auger 76 carries the dirt and dust which normally collects in the bottom of the heating chamber to the rear end 14 of the unit and discharges it outwardly therefrom, thereby substantially eliminating a fire hazard.

A motor 79 having a double pulley is mounted within the housing at one side thereof and is connected by a belt 80 which drives an agitator indicated generally as 81. As best shown in Figs. 1, 3 and 4, this agitator extends transversely of the unit and is positioned immediately adjacent to and above the drying conveyor 31. A second belt 82 extends from the motor 79 to a pulley 83 which is mounted on one end of the shaft carrying the auger 59. Thus the motor 79 serves to drive the auger 59 and the agitator 81.

The agitator 81 is comprised of a shaft 84 upon which a plurality of discs 85 is mounted, at least one of these discs being secured at each end of the agitator to the shaft. Extending between these discs adjacent the circumferential portions thereof and longitudinally of the agitator are a plurality of strips of angled metal 86. Secured to these strips of angled metal 86 and extending outwardly therefrom is a strip of belting 87. This belting extends throughout the length of each of the strips and extends outwardly from the discs

85 so that the outer edge thereof brushes across the upper surface of the drying conveyor 31 as the agitator 81 rotates. This agitator serves to draw the more highly dried portions of the grain, which will be immediately adjacent to the upper surface of the conveyor, to the upper surface of the grain stratum and brings the more damp portions of the grain stratum downwardly in close proximity to the upper surface of the conveyor so as to facilitate the drying of the stratum.

A blast-type oil burner 88, which can best be seen in Figs. 1 and 2, is provided to supply the heat for the drying operation. As seen in Fig. 1, this burner is provided with an oil pump 89, a pressure blower 90, and a motor 91 to drive the two latter elements. An oil pressure regulator 92 and a solenoid valve 93 along with a filler 94, is provided to complete the combustion unit. A foot switch 95 is provided to start the unit and a fire eye 96 serves to maintain the unit in operation after it has once been started. A high limit control 97 prevents the temperature within the drying chamber from reaching a level where there would be substantial danger of fire. A similar control (not shown) is provided to stop the entire unit in the event the temperature of the air as it leaves the grain exceeds 160° F., a limit set by fire safety authorities.

Cool air is drawn inwardly through the cool air inlet 24 and is mixed with the hot combustion gases discharged by the burner 88 and are drawn rearwardly by a huge fan 98 as can best be seen in Fig. 1. The air is driven rearwardly by the huge fan 98 and upwardly through the drying conveyor and the stratum of grain thereupon throughout the entire length of the drying conveyor. This fan 98 is provided with a motor 99 which is connected to the fan shaft 100 by a belt 101 and a pulley 102. The belt 101 and the fan shaft 100 are encased in a metal tube 103 which communicates with the exterior so that as the fan 98 rotates, cool air is drawn through this tube to prevent the fan shaft 100 from burning out its bearings.

Above the cooling conveyor 62 and mounted inside the air intake 25 of the cooling chamber, is positioned a fan 104 which is driven by a motor 105. This fan draws the cool air inwardly and drives it downwardly through the grain stratum upon the upper surface of the cooling conveyor 62 to cool it sufficiently so that the grain may be stored immediately upon its discharge from the unit. A panel 106 extends inwardly to the inner wall of the cooling chamber and directly beneath the fan 104 to prevent the air from being turned immediately downwardly against the stratum of grain and permitting the flow of air to dig an opening in the stratum of grain and thereby destroy the cooling effectiveness of the unit. This same panel 106 extends slightly forwardly from the fan so that the air flow will be applied indirectly rather than directly to the stratum of grain when the drying operation is initiated.

In operation, the grain passes downwardly through the hopper 27 and is deposited upon the upper surface of the drying conveyor 31. The fan 98 forces the hot combustion gases discharged by the burner 88 and mixed with some cool air drawn through the air inlet 24, rearwardly into the confines of the hot chamber and upwardly through the porous conveyor 31. The hot moisture-laden air is discharged through the open portion 16 of the top of the unit. It should be noted that the grain travels the entire length of the unit and when it reaches the rear end of the

unit it is discharged into the trough 58 and thereupon transported by the auger 59 into the chute 60 from which it is discharged upon the receiving end 65 of the cooling conveyor. From there the grain passes forwardly again throughout the entire length of the unit until it is discharged through the discharge outlet 67. The cool air is drawn in by the fan 104 and driven downwardly through the stratum of grain upon the cooling conveyor 62, this air passing outwardly through the open bottom of the cooling chamber. It should be noted that this entire unit is designed to be mounted several feet above the ground so that no difficulty is encountered in the free escape of the air which has passed through the cooling conveyor.

It can be readily seen that I have substantially increased the capacity of such a drying unit by permitting the grain to pass throughout the entire length of the unit and then concentrating the grain into a relatively narrow area and drawing it again throughout the entire length of the unit in an opposite direction and discharging it from the end at which the grain enters the unit. In this manner, I have substantially increased the capacity of the unit since the entire length of the unit is used for drying purposes, and it is no longer necessary to utilize a substantial portion of the length of the unit for the purpose of cooling the grain. In addition, it can be readily seen that I have provided this added capacity without increasing the amount of equipment and materials necessary for construction of the unit so that the entire unit may be manufactured at a cost comparable or even less than the cost of the units previously known in the grain drying industry.

It will, of course, be understood that various changes may be made in the form, details, arrangement and proportions of the various parts without departing from the scope of my invention.

What I claim is:

1. A continuous grain dryer having in combination an elongated housing having a grain intake and a grain discharge outlet, a longitudinal partition dividing the interior of said housing into a hot chamber and a cooling chamber, a blast-type burner mounted in the lower part of one end portion of said housing and directed longitudinally of said housing, an endless porous conveyor extending throughout substantially the length of said housing within said hot chamber and running in a predetermined direction and having a receiving end and a discharging end, said hot chamber having an air inlet below said conveyor and an air outlet above said conveyor and said burner discharging hot air into said hot chamber below said conveyor, means for delivering a stratum of grain from said grain intake to the receiving end of said conveyor and depositing the same thereupon, a second endless porous conveyor extending substantially throughout the length of said housing within said cooling chamber and traveling in an opposite direction than said first mentioned conveyor and having a receiving end and having a discharging end which discharges the grain outwardly through said grain discharge outlet, said cooling chamber having an air inlet and an air outlet one of which is disposed above and the other of which is disposed below said second mentioned conveyor, means for receiving the grain from the discharging end of said first mentioned conveyor as it is discharged therefrom and for depositing the same upon the receiving end

of said second mentioned conveyor, means for driving the hot air from said burner upwardly through said first mentioned conveyor and the stratum of grain thereupon and outwardly through said hot chamber's air outlet, and means for driving cool air through said second mentioned conveyor and the stratum of grain thereupon and outwardly through said cooling chamber's air outlet.

2. A continuous grain dryer having in combination an elongated housing having a grain intake and a discharge outlet, a longitudinal partition dividing the interior of said housing into a hot chamber and a cooling chamber, a blast-type burner mounted in the lower part of one end portion of said housing and directed longitudinally thereof, an endless porous conveyor extending throughout substantially the length of said housing within said hot chamber and running in a predetermined direction and having a receiving end and a discharging end, said hot chamber having an air inlet below said conveyor and an air outlet above said conveyor and said burner discharging hot air into said hot chamber below said conveyor, means for delivering a stratum of grain from said grain intake to the receiving end of said conveyor and depositing the same thereupon, a second endless porous conveyor extending substantially throughout the length of said housing within said cooling chamber and traveling in an opposite direction than said first mentioned conveyor and having a receiving end and having a discharging end which discharges the grain through said grain discharge outlet, said cooling chamber having an air inlet and an air outlet one of which is disposed above and the other of which is disposed below said second mentioned conveyor, the receiving end of said second mentioned conveyor receiving the grain discharged from the discharging end of said first mentioned conveyor, mechanism for driving hot air from said burner upwardly through said first mentioned conveyor and the stratum of grain thereupon and outwardly through said hot chamber's air outlet, and mechanism for driving cool air through said second mentioned conveyor and the stratum of grain thereupon and outwardly through said cooling chamber's air outlet.

3. A continuous grain dryer having in combination an elongated housing having a grain intake and a grain discharge outlet, a longitudinal partition dividing the interior of said housing into a hot chamber and a cooling chamber, a blast-type burner mounted in the lower part of one end portion of said housing and directed longitudinally thereof, an endless porous conveyor extending throughout substantially the length of said housing within said hot chamber and running in a predetermined direction and having a receiving end and a discharging end, said hot chamber having an air inlet below said conveyor and an air outlet above said conveyor, said burner discharging hot air into said hot chamber below said conveyor, means for delivering a stratum of grain from said grain intake to the receiving end of said conveyor and depositing the same thereupon, a second endless porous conveyor extending substantially throughout the length of said housing within said cooling chamber and traveling in an opposite direction than said first mentioned conveyor and having a receiving end and having a discharging end which discharges the grain outwardly through said grain discharge outlet, said cooling chamber having an air inlet and an air outlet one of which is disposed above and the other of which is disposed below said second mentioned conveyor, means for receiving the grain from the discharging end of said first mentioned conveyor as it is discharged therefrom and for depositing the same upon the receiving end of said second mentioned conveyor, mechanism for driving the hot air from said burner upwardly through said first mentioned conveyor and the stratum of grain thereupon and outwardly through said hot chamber's air outlet, and mechanism for drawing cool air into said cooling chamber through its air inlet and for driving such cool air through said second mentioned conveyor and the stratum of grain thereupon and outwardly through said cooling chamber's air outlet.

5. A continuous grain dryer having in combination an elongated housing having a grain intake and a grain discharge outlet, a longitudinal partition dividing the interior of said housing into a larger hot chamber and a cooling chamber, said cooling chamber extending longitudinally of said housing along only one side portion thereof, a blast-type burner mounted in the lower part of one end portion of said housing and along the other side portion thereof laterally of said cooling chamber, an endless porous conveyor extend-

10 and the stratum of grain thereupon and outwardly through said hot chamber's air outlet, and mechanism for drawing cool air into said cooling chamber through its air inlet and for driving the same downwardly through said second mentioned conveyor and the stratum of grain thereupon and outwardly through said cooling chamber's air outlet.

15 4. A continuous grain dryer having in combination an elongated housing having a grain receiving end and a grain discharging outlet, a longitudinal partition dividing the interior of said housing into a hot chamber and a cooling chamber, a blast-type burner mounted in the lower part of one end portion of said housing and directed longitudinally thereof, an endless porous conveyor extending throughout substantially the length of said housing within said hot chamber and running in a predetermined direction and having a receiving end and a discharging end, said hot chamber having an air inlet below said conveyor and an air outlet above said conveyor and said burner discharging hot air into said hot chamber below said conveyor, a hopper in the receiving end of said housing adapted to deliver continuously a stratum of grain upon the receiving end of said conveyor, a rotary agitator mounted directly above and immediately adjacent to said conveyor and extending transversely thereacross in position to engage

20 the stratum of grain thereupon and agitate the same, a second endless porous conveyor extending substantially throughout the length of said housing within said cooling chamber and traveling in a direction opposite than said first mentioned conveyor and having a receiving end and a discharging end which discharges the grain outwardly through said grain discharge outlet, said cooling chamber having an air inlet and an air outlet one of which is disposed above and the other of which is disposed below said second mentioned conveyor, means for receiving the grain from the discharging end of said first mentioned conveyor as it is discharged therefrom and for depositing the same upon the receiving end of said second mentioned conveyor, mechanism for driving the hot air from said burner upwardly through said first mentioned conveyor and the stratum of grain thereupon and outwardly through said hot chamber's air outlet, and mechanism for drawing cool air into said cooling chamber through its air inlet and for driving such cool air through said second mentioned conveyor and the stratum of grain thereupon and outwardly through said cooling chamber's air outlet.

25 5. A continuous grain dryer having in combination an elongated housing having a grain intake and a grain discharge outlet, a longitudinal partition dividing the interior of said housing into a larger hot chamber and a cooling chamber, said cooling chamber extending longitudinally of said housing along only one side portion thereof, a blast-type burner mounted in the lower part of one end portion of said housing and along the other side portion thereof laterally of said cooling chamber, an endless porous conveyor extend-

ing throughout substantially the length of said housing within said hot chamber and running in a predetermined direction and having a receiving end and a discharging end, said hot chamber having an air inlet below said conveyor and an air outlet above said conveyor and said burner discharging hot air into said chamber below said conveyor, means for delivering a stratum of grain from said grain intake to the receiving end of said conveyor and depositing the same thereupon, a second endless porous conveyor extending substantially throughout the length of said housing within said cooling chamber and traveling in an opposite direction than said first mentioned direction and having a receiving end and having a discharging end which discharges the grain outwardly through said grain discharge outlet, said cooling chamber having an air inlet and an air outlet one of which is disposed above and the other of which is disposed below said second mentioned conveyor, means for transferring the grain from the discharging end of said first mentioned conveyor as it is discharged therefrom to the receiving end of said second mentioned conveyor, mechanism for driving the hot air from said burner upwardly through said first mentioned conveyor and the stratum of grain thereupon and outwardly through said hot chamber's air outlet, and mechanism for drawing cool air into said cooling chamber through its air inlet and for driving the same through said second mentioned conveyor and the stratum of grain thereupon and outwardly through said cooling chamber's air outlet.

6. A continuous grain dryer having in combination an elongated housing having a grain intake and a grain discharge outlet, a longitudinal partition dividing the interior of said housing into a hot chamber and a cooling chamber, a blast-type burner mounted in the lower part of one end portion of said housing and directed longitudinally of said housing, an endless conveyor extending horizontally throughout substantially the length of said housing within said hot chamber and running in a predetermined direction and having a receiving and a discharging end, said hot chamber having an air inlet below said conveyor and an air outlet above said conveyor and said burner discharging hot air into said hot chamber below said conveyor, means for delivering a stratum of grain from said grain intake to the receiving end of said conveyor and depositing the same thereupon, a second endless porous conveyor extending substantially throughout the length of said housing within said cooling chamber and traveling in an opposite direction than said first mentioned conveyor and having a receiving end and having a discharging end which discharges the grain outwardly through said grain discharge outlet, at least one of said conveyors including a plurality of closely adjacent, parallel, transversely extending porous panels, each of said panels being hingedly connected at its opposite ends to its adjacent panel to form the endless conveyor, said cooling chamber having an air inlet and an air outlet one of which is disposed above and the other of which is disposed below said second mentioned conveyor, means for receiving the grain from the discharging end of said first mentioned conveyor as it is discharged therefrom and for depositing the same upon the receiving end of said second mentioned conveyor, mechanism for driving the hot air from said burner upwardly through said first mentioned conveyor and the stratum of grain thereupon and outwardly through said cooling chamber's air outlet.

thereupon and outwardly through said hot chamber's air outlet, and mechanism for drawing cool air into said cooling chamber through its air inlet and driving the same through said second mentioned conveyor and the stratum of grain thereupon and outwardly through said cooling chamber's air outlet.

7. A continuous grain dryer having in combination an elongated housing having a grain intake and a grain discharge outlet, a longitudinal partition dividing the interior of said housing into a larger hot chamber and a cooling chamber, said cooling chamber extending longitudinally of said housing and the major portion thereof extending throughout only the lower portion of said housing and along one side thereof, a blast-type burner mounted in the lower part of one end portion of said housing and directed longitudinally of said housing, an endless porous conveyor extending throughout substantially the length of said housing within said hot chamber and running in a predetermined direction and having a receiving and a discharging end, said hot chamber having an air inlet below said conveyor and an air outlet above said conveyor and said burner discharging hot air into said hot chamber below said conveyor, means for delivering a stratum of grain from said grain intake to the receiving end of said conveyor and depositing the same thereupon, a second endless porous conveyor extending substantially throughout the length of said housing within said cooling chamber and traveling in an opposite direction than said first mentioned conveyor and having a receiving end and having a discharging end which discharges the grain outwardly through said grain discharge outlet, said cooling chamber having an air inlet and an air outlet one of which is disposed above and the other of which is disposed below said second mentioned conveyor, means for receiving the grain from the discharging end of said first mentioned conveyor as it is discharged therefrom and for depositing the same upon the receiving end of said second mentioned conveyor, mechanism for driving the hot air from said burner upwardly through said first mentioned conveyor and the stratum of grain thereupon and outwardly through said hot chamber's air outlet, and mechanism for drawing cool air into said cooling chamber through its air inlet and for driving such cool air through said second mentioned conveyor and the stratum of grain thereupon and outwardly through said cooling chamber's air outlet.

8. A continuous grain dryer having in combination an elongated housing having a grain intake and a grain discharge outlet, a longitudinal partition dividing the interior of said housing into a hot chamber and a cooling chamber, a blast-type burner mounted in the lower part of one end portion of said housing and directed longitudinally of said housing, an endless porous conveyor extending throughout substantially the length of said housing within said hot chamber and running in a predetermined direction and having a receiving end and a discharging end, said hot chamber having an air inlet below said conveyor and an air outlet above said conveyor and said burner discharging hot air into said hot chamber below said conveyor, said housing having walls defining the lower portion of said hot chamber which meet at the bottom in a generally V-shape, means for delivering a stratum of grain from said grain intake to the receiving end of said conveyor and depositing the same

thereupon, a second endless porous conveyor extending substantially throughout the length of said housing within said cooling chamber and traveling in an opposite direction than said first mentioned conveyor and having a receiving end and having a discharging end which discharges the grain outwardly through said grain discharge outlet, a clean-out auger extending longitudinally of said housing throughout substantially the length thereof and rotatably mounted in the bottom of said hot chamber at the base of said V-shaped walls for cleaning out the dust normally collecting therewithin, said cooling chamber having an air inlet and an air outlet one of which is disposed above and the other of which is disposed below said second mentioned conveyor, means for receiving the grain from the discharging end of said first mentioned conveyor as it is discharged therefrom and for depositing the same upon the receiving end of said second mentioned conveyor, mechanism for driving the hot air from said burner upwardly through said first mentioned conveyor and the stratum of grain thereupon and outwardly through said hot chamber's air outlet, and mechanism for drawing cool air into said cooling chamber through its air inlet and for driving such cool air through said second mentioned conveyor and the stratum of grain thereupon and outwardly through said cooling chamber's air outlet.

9. A continuous grain dryer having in combination an elongated housing having a grain intake and a grain discharge outlet, a longitudinal partition dividing the interior of said housing into a hot chamber and a cooling chamber, a blast-type burner mounted in the lower part of one end portion of said housing and directed longitudinally of said housing, an endless porous conveyor extending throughout substantially the length of said housing within said hot chamber and running in a predetermined direction and having a receiving end and having a discharging end, said hot chamber having an air inlet below said conveyor, said burner discharging hot air into said hot chamber below said conveyor, a blower mounted within said hot chamber and moving the hot air from said burner forwardly through said hot chamber and drawing cool air through said air inlet and mixing the same with said hot air and driving it upwardly through said conveyor, means for delivering a stratum of grain from said grain intake to the receiving end of said conveyor and depositing the same thereupon, a second endless porous conveyor extending substantially throughout the length of said housing within said cooling chamber and traveling in an opposite direction than said first mentioned conveyor and having a receiving end and having a discharging end and discharging the grain outwardly through said grain discharge outlet, said cooling chamber having an air inlet and an air outlet one of which is disposed above and the other of which is disposed below said second mentioned conveyor, means for receiving the grain from the discharging end of said first mentioned conveyor as it is discharged therefrom and for depositing the same upon the receiving end of said second mentioned conveyor, mechanism for driving the hot air from said burner upwardly through said first mentioned conveyor and the stratum of grain thereupon and outwardly through said hot chamber's air outlet, and mechanism for drawing cool air into said cooling chamber through its air inlet and for driv-

ing the same through said second mentioned conveyor and the stratum of grain thereupon and outwardly through said cooling chamber's air outlet.

- 5 10. A continuous grain dryer having in combination an elongated housing having a grain intake and a grain discharge outlet, a longitudinal partition dividing the interior of said housing into a hot chamber and a cooling chamber, a blast-type burner mounted in the lower part of one end portion of said housing and directed longitudinally thereof, an endless porous conveyor extending throughout substantially the length of said housing within said hot chamber and running in a predetermined direction and having a receiving end and a discharging end, said hot chamber having an air inlet below said conveyor and an air outlet above said conveyor and said burner discharging hot air into said hot chamber below said conveyor, means for delivering a stratum of grain from said grain intake to the receiving end of said conveyor and depositing the same thereupon, a second endless porous conveyor extending substantially throughout the length of said housing within said hot chamber and traveling in an opposite direction than said first mentioned conveyor and having a receiving end and having a discharging end which discharges the grain outwardly through said 20 grain discharge outlet, said cooling chamber having an air inlet above and an air outlet below said second mentioned conveyor, a blower drawing cool air through the inlet of said cooling chamber and forcing the same downwardly through said second mentioned conveyor and the stratum of grain thereupon to cool the latter, means for receiving the grain from the discharging end of said first mentioned conveyor as it is discharged therefrom and for depositing the same 25 upon the receiving end of said second mentioned conveyor, mechanism for driving the hot air from said burner through said first mentioned conveyor and the stratum of grain thereupon and outwardly through said hot chamber's air outlet, and mechanism for drawing cool air into said cooling chamber through its air inlet and for driving the same through said second mentioned conveyor and the stratum of grain thereupon and outwardly through said cooling chamber's air outlet.

11. A continuous grain dryer having in combination an elongated housing having a grain intake and a grain discharge outlet, a longitudinal partition dividing the interior of said housing into a hot chamber and a cooling chamber extending along one side only of said housing, a blast-type burner mounted in the lower part of one end portion of said housing and directed longitudinally thereof, an endless porous conveyor extending throughout substantially the length of said housing within said chamber and across the entire width thereof and running in a predetermined direction and having a receiving end and a discharging end, said hot chamber having an air inlet below said conveyor and an air outlet above said conveyor, said burner discharging hot air into said hot chamber below said conveyor, means for delivering a stratum of grain from said grain intake to the receiving end of said conveyor and depositing the same thereupon, a second endless porous conveyor extending substantially throughout the length of said housing within said cooling chamber and traveling in an opposite direction than said first mentioned conveyor and having a receiving end and

having a discharging end which discharges the grain outwardly through said grain discharge outlet, said cooling chamber having an air inlet and an air outlet one of which is disposed above and the other of which is disposed below said second mentioned conveyor, mechanism for receiving the grain from the discharging end of said first mentioned conveyor as it is discharged therefrom and for moving the same laterally toward one side of said housing and for depositing the same upon the receiving end of said second mentioned conveyor, mechanism for driving the hot air from said burner upwardly through said first mentioned conveyor and the stratum of grain thereupon and outwardly through said hot chamber's air outlet, and mechanism for drawing cool air into said cooling chamber through its air inlet and for driving the same through said second mentioned conveyor and the stratum of grain thereupon outwardly through said cooling chamber's air outlet.

12. A continuous grain dryer having in combination an elongated housing having a grain intake and having a grain discharge outlet, a longitudinal partition dividing the interior of said housing into a hot chamber and a cooling chamber, a blast-type burner mounted in one end portion of said housing and directed longitudinally thereof, an endless porous conveyor extending throughout substantially the length of said housing within said hot chamber and running in a predetermined direction and having a receiving end and a discharging end, said hot chamber having an air inlet and an air outlet one of which is disposed above and the other of which is disposed below said conveyor, said burner discharging hot air into said hot cham-

ber adjacent said air inlet, mechanism for delivering a stratum of grain from said grain intake to the receiving end of said conveyor and depositing the same thereon, a second endless porous conveyor extending substantially throughout the length of said housing within said cooling chamber and traveling in an opposite direction than said first mentioned conveyor and having a receiving end and having a discharging end which discharges the grain outwardly through said grain discharge outlet, said cooling chamber having an air inlet and an air outlet one of which is disposed above and the other of which is disposed below said second mentioned conveyor, means for receiving the grain from the discharging end of said first mentioned conveyor as it is discharged therefrom and for depositing the same upon the receiving end of said second mentioned conveyor, mechanism for driving the hot air from said burner through said first mentioned conveyor throughout its length and outwardly through said hot chamber's air outlet, and mechanism for drawing cool air into said cooling chamber through its air inlet and for discharging the same through said second mentioned conveyor and the stratum of grain thereupon and outwardly through said cooling chamber's air outlet.

BEN L. TOMLINSON.
